(57) **CLAIM**

The ornamental design for an orthodontic screw, as shown and described.

DESCRIPTION

FIG. 1 is a perspective view of an orthodontic screw showing our new design;

FIG. 2 is front elevation thereof;

FIG. 3 is a rear elevation thereof;

FIG. 4 is a left side elevation thereof;

FIG. 5 is a right side elevation thereof;

FIG. 6 is a top plan view thereof; and,

FIG. 7 is a bottom plan view thereof.

The broken line shown in the drawings are included for the purpose of illustrating environmental structure and form no part of the claimed design.
